CLAIM

We claim the ornamental design for a label clip for dividers, as shown and described.

DESCRIPTION

FIG. 1 is a top right perspective view of a label clip for dividers.

FIG. 2 is a bottom right rear perspective view thereof.

FIG. 3 is a front view thereof.

FIG. 4 is a rear view thereof.

FIG. 5 is a top plan view thereof.

FIG. 6 is a bottom plan view thereof.

FIG. 7 is a side elevation view thereof; and,

FIG. 8 is a top right perspective view thereof showing the label clip for dividers with a bin and dividers.

In the drawings, the broken lines illustrate environment and form no part of the claimed design.

1 Claim, 5 Drawing Sheets
